UNITED STATES PATENT OFFICE.

CHAUNCEY W. DODGE, OF NEWBURYPORT, MASSACHUSETTS, ASSIGNOR TO UNITED SHOE MACHINERY COMPANY, OF PATERSON, NEW JERSEY, A CORPORATION OF NEW JERSEY.

SOLE-PRESSING MACHINE.

1,164,794.

Specification of Letters Patent. Patented Dec. 21, 1915.

Application filed November 3, 1911. Serial No. 658,298.

To all whom it may concern:

Be it known that I, CHAUNCEY W. DODGE, a citizen of the United States, residing at Newburyport, in the county of Essex and State of Massachusetts, have invented certain new and useful Improvements in Sole-Pressing Machines; and I do hereby declare the following to be a full, clear, and exact description of the invention, such as will enable others skilled in the art to which it appertains to make and use the same.

The present invention relates to sole pressing machines, and more particularly to machines of this type which are employed for molding the shanks of soles which have been incorporated in boots and shoes.

In the manufacture of all types of boots and shoes, it is desirable to secure a rounded shank, as this type of shank has several advantages, some of which are that it adds to the finish and appearance of the shoe sole and greatly stiffens the sole against longitudinal bending at the shank. This latter feature is particularly advantageous in turn shoes, as shoes of this type are necessarily of a light construction and have a tendency to become bent and cracked at the shank during the manufacture of the shoe. With existing machines for operating upon shoe soles and with the ordinary methods of manufacture at present in use, it is not possible to secure the requisite curvature of the shank portion of the sole owing to the fact that the lasts upon which the shoes are made and which are retained in the shoes during the manufacture are of such a construction that the pressing device, whether it be a pressing form or a roll will strike and mar the vamp of the shoe if it is constructed with a sufficiently great curvature to impart the desired transverse curvature to the shank of the sole.

The object of the present invention is to secure a firm rounded shank having a greater transverse curvature than can be secured upon the ordinary last without marring the upper or otherwise spoiling the finished appearance of the shoe or breaking the inseam fastenings which secure the upper to the sole.

With this object in view, one feature of the invention contemplates the provision of an incomplete supporting member arranged to extend forward only throughout the shank of the shoe, and a coöperating press-

ing member which is arranged to operate upon the sole only over the limited area supported by the first mentioned member.

A further feature of the invention consists in the provision of a shoe supporting member which is narrower than the last of the shoe to allow the upper to hang down freely upon both sides, and a coöperating sole pressing member provided with a pressing face having a greater transverse curvature than the angle of the vamp in the finished shoe.

A still further feature of the invention comprises a pressing member having a transversely curved pressing face arranged to engage with opposite margins of the sole simultaneously, and a coöperating member for supporting the shoe at the shank inside of the inseam in order to maintain the fastenings which secure the upper to the sole unbroken during the pressing operation.

Still further features of the invention consist of certain novel features of construction, combinations and arrangements of parts hereinafter described and claimed, the advantages of which will be apparent to those skilled in the art from the following description.

In the accompanying drawings illustrating the preferred form of the invention Figure 1 represents a side elevation of a machine embodying the several features of the invention in their preferred forms, and shown with the supporting form arranged in an inoperative position; Fig. 2 is a side elevation, partly in section, of the machine showing the shoe supporting form and various coöperating elements in an operative position; Fig. 3 is a front elevation of the machine; Fig. 4 is a section upon the line 4—4 of Fig. 2, looking in the direction of the arrow; and Fig. 5 is a cross section of the shoe supporting member and leveling roll coöperating therewith and showing the manner in which a shoe is supported upon the form and the operation of the roll thereon.

Substantially all welt and turn shoes are strengthened at the shank by the addition of a shank stiffener, and the rounding of the shank transversely not only aids the shank stiffener in strengthening the sole, but at the same time seats the shank stiffener more securely in its position. It will be readily understood by those skilled in the art that

the rounding of the sole has the same effect upon the longitudinal bending of the sole that the ribbing or flanging of a thin flat plate has upon the resistance to bending of that plate. Turn and welt shoes are manufactured upon a wooden last which remains in the shoe until the upper and sole are permanently secured together. In order to secure the requisite strength in cross section of the last and to properly fill out the vamp of the shoe, it is necessary for the last to be fairly flat at the portion which supports the shank and that the body portion of the last which supports the vamp have a certain inclination relatively to the bottom of the last. The angle which this portion of the last makes with the bottom of the last may be conveniently designated as the angle of the vamp in the finished shoe.

20 The present machine operates upon the shoe when off the last and the shank molding operation takes place at any convenient period in the manufacture of the shoe. The shoe is supported upon a form which is narrower than the last of the shoe to allow the upper to hang down loosely upon both sides of the form without interfering with the operation of the pressing member, thereby avoiding any danger of the pressing member striking and marring the upper during the molding of the shank.

30

In the illustrated embodiment of the invention, the shoe is supported by a form indicated at 1, which cooperates with a leveling roll indicated at 2 to mold the shank of the shoe. The form and roll are provided with pressing surfaces 3 and 4 respectively, which are curved transversely to impart the proper shape to the shank, and the transverse curvature of the pressing face 4 is greater than the angle of the vamp in the finished shoe. In order to maintain the inseam fastenings unbroken during the pressing operation, the form 1 is arranged to support the shoe at the shank inside of the inseam so that the opposite margins of the sole are free to be pressed downwardly by the leveling roll 2. As the form carrying the shoe is moved into a pressure producing position, the surface of the roll engages with opposite margins of the sole and presses them downwardly until the entire width of the shank at the line of pressure of the leveling roll conforms exactly to the curvature of the pressing face 4.

55 The shoe supporting form is normally retained by gravity in an inoperative position or a position of presentation as it may be termed, which is removed from the leveling roll and is conveniently accessible to the operator for the putting on of a new shoe or the removal of a finished one. The form is moved into position beneath the roll by mechanism under the control of the operator and by varying the pressure upon a suit-

able control pedal any desired pressure can be secured upon the shoe. The form extends forward only throughout the shank of the shoe and the shoe is clamped to the form during the leveling operation by a heel clamp which operates automatically upon the movement of the form into position beneath the roll. The roll is freely rotatable and is continuously moved back and forth to cause the roll to traverse longitudinally of the shank. The extent of this movement may be varied to accommodate the machine for different length shanks through the provision of suitable adjusting mechanism. The shoe supporting form is made integral with a curved lever 10 pivoted at 11 upon the frame of the machine. The curved lever under the action of gravity normally swings down to the position shown in Fig. 1, but is raised into an operative position beneath the roll by an operating arm 12 pivotally connected to the frame of the machine at 13. This operating arm has a projection 14 formed thereon which is connected to a suitable treadle by a link 15. The operating arm is normally retained in an inoperative position as shown in Fig. 1 by a spring 16. The mounting of the treadle (not shown) is such that upon a depression of the treadle the link 15 is raised to move the operating arm to the left against the action of the spring 16, and raise the lever 10. In order to retain the shoe supporting form 1 yieldingly in engagement with the leveling roll, a plate 17 is connected to the lever 10 at 18 and is yieldingly forced away from the lever by a spring 19, interposed between the lever and the free end of the plate. The lower face of the plate is provided with a working surface 20 which engages with a roll 21 journaled in the upper end of the arm 12, so that as the roll 21 rides along the face 20, the curved lever 10 is yieldingly forced upward by the spring 19. A stop 22 serves to limit the movement of the plate 17 under the action of the spring 19. In order to retain the shoe firmly upon the form, a clamp carrying arm 23 is pivotally connected to the frame of the machine at 24. This arm is normally held down by a spring 25 and a clamping member 26 is arranged to contact with the sole of the shoe at the heel when the shoe supporting form is raised into an operative position. The clamping member 26 is pivotally connected to the outer end of the arm 23 at 27 and is provided with ratchet teeth arranged to engage with the surface of the sole and force the counter of the shoe firmly against the heel portion of the form, thus seating the shoe properly upon the form.

60 The leveling roll 2 is journaled in the free end of an arm 30 which is pivotally connected at 31 to the frame of the machine. A link 32 is connected to the arm midway of

its ends and serves to impart an oscillatory movement to the arm and roll. The link is actuated by a train of mechanism comprising a drive pulley 33 mounted upon a main 5 drive shaft 34, and a pair of intermeshing gears 35 and 36 mounted upon the drive shaft 34, and counter shaft 37 respectively. A crank 38 is mounted upon the shaft 37 and oscillates a lever 39 through a cross head 10 and slide connection 40. The lever 39 is formed as a bell crank and is pivotally connected to the frame of the machine at 41. The opposite arm of the lever 39 is connected to the lever 32 at 42 so that upon rotating 15 the crank 38, the lever 39 is oscillated to impart the desired movement to the roll 1. In order to vary the extent of movement of the roll, mechanism is provided for moving the point of connection 42 toward or from the 20 pivotal point 41 of the bell crank 39. To this end the link 32 is pivotally connected to a curved slide 43 which is retained in curved ways 44, formed in one face of the lever 39. A rack 45 is cut upon the rear 25 face of the slide 43 and meshes with a pinion 46 journaled in the pivot pin 41. This pinion meshes upon its opposite side with a segmental gear 47 formed upon one end of the bell crank lever 48, pivoted to the frame 30 of the machine at 49. The free end of the bell crank 48 is provided with a spring 50 pressed detent arranged to be inserted in any one of a series of recesses 51 formed in the side of the machine. Thus by adjusting 35 the position of the lever 48 the pinion is rotated to correspondingly adjust the slide 43 and vary the travel of the roll 2.

While it is preferred to employ the specific construction and arrangement of parts 40 shown and described, it will be understood that this construction and arrangement is not essential except so far as specified in the claims, and may be changed or modified without departing from the broader features 45 of the invention.

Having thus described the invention, what is claimed is:—

1. A sole pressing machine, having in combination, a member for supporting the

shoe after the last has been removed arranged to project within the shoe and support the shank portion of the shoe while leaving the forepart of the shoe unsupported, and a pressing member arranged to operate upon the shank portion of the sole and 50 coöperate with the supporting member to press the shank portion of the sole and impart the desired transverse curvature thereto.

2. A sole pressing machine, having, in combination, a shoe supporting member 60 which is narrower at the shank supporting portion than the shank portion of the last of the shoe to allow the upper to hang down freely upon both sides, and a sole pressing member coöperating with the shoe supporting member to press the shank portion of the shoe sole and impart the desired transverse curvature thereto.

3. A sole pressing machine, having, in combination, a pressing member having a 70 transversely curved pressing face arranged to engage with opposite margins of the sole simultaneously, and a coöperating member projecting within the upper and supporting the sole at the shank inside of the inseam 75 while leaving the shank portion of the sole outside of the inseam unsupported in order to maintain the fastenings which secure the upper to the sole unbroken during the pressing operation, substantially as described. 80

4. A sole pressing machine, having in combination, a shoe supporting member which is narrower at the shank supporting portion than the shank portion of the last to allow the upper to hang down freely upon both 85 sides and which is arranged to support the shank portion of the shoe sole leaving the forepart of the shoe unsupported, and a pressing member arranged to operate upon the shank portion of the sole and coöperate 90 with the supporting member to press the shank portion of the sole and impart the desired transverse curvature thereto.
